CLAIM

The ornamental design for an automatic diskette loader, substantially as shown and described.

DESCRIPTION

FIG. 1 is a perspective view of an automatic diskette loader embodying my new design;

FIG. 2 is a side elevational view thereof showing the side opposite that shown in FIG. 1;

FIG. 3 is a front elevational view thereof;

FIG. 4 is a top plan view thereof;

FIG. 5 is a bottom plan view thereof; and

FIG. 6 is a rear elevational view thereof.
